ROTARY BIT

Anthony E. Carlson, Los Angeles, Calif.

Application October 31, 1932. Serial No. 640,484

14 Claims. (Cl. 255—73)

My invention relates to rotary drilling devices and relates particularly to a rotary bit having a removable head supported at the lower end of a bit body.

It is an object of the invention to provide a rotary bit having a body of simple and durable form with a cutter head detachably secured thereto in a simple and sturdy manner, the body having reamer recesses formed therein, the lower ends of which recesses provide openings for receiving a connecting part which extends upwardly from the cutter head.

A further object of the invention is to provide a bit of the above character in which the upper portion of the removable cutter head forms a lower wall for the reamer recesses and may serve as means for securing the reamer elements in the recesses, so that the removal of the cutter head from the bit body also releases the reamer elements so that they may be removed from the reamer recesses, and so that the operation of securing the cutter head in engagement with the lower end of the bit body results also in locking the reamer elements in the reamer recesses.

It is a further object of the invention to provide a rotary drill bit having roller type reamer elements supported in roller bearings, whereby to maintain a free rotation of the reamers during the operation of the drill bit and consequently to avoid the sticking of the reamer elements, whereupon they quickly become worn flat and tend to bind the bit in the hole, especially where rock formations are being penetrated.

A further object of the invention is to provide a drill bit having a reamer structure of simple form in which the reamer elements are received in reamer recesses formed by use of an opening extending diametrically through the bit or reamer body, and in which the bearings for the reamer elements are located in the ends of the plates which extend diametrically across the body.

Further objects and advantages of the invention will be set forth in the following part of the specification.

Referring to the drawings, which are for illustrative purposes only,

Fig. 1 is a partly sectioned elevational view showing a preferred embodiment of my new bit.

Fig. 2 is a partly sectioned side view corresponding to Fig. 1.

Fig. 3 is a cross section on a plane represented by the line 3—3 of Fig. 2.

Fig. 4 is a fragmentary vertical section show-

ing how the reamer elements may be secured in the reamer recesses solely by use of the diametrically extending plates.

Fig. 5 is a fragmentary, vertically sectioned view showing an alternative means for securing the reamer elements.

Fig. 6 is a cross section on a plane represented by the line 6—6 of Fig. 5.

As shown in Figs. 1 and 2, I provide a bit body 11 having an internally threaded cylindrical box 12 at its upper end adapted for engagement with a threaded pin 13 on the lower end of a string of drill pipe or drill collar 14. Extending downwardly from the box or fitting 12 is a flat body portion 15 having a thickness, 70 as shown in Fig. 1, substantially equal to the diameter of the box 12 and having a width, as shown in Fig. 2, somewhat greater than the diameter of the box 12, this flattened form of body providing within the well 18 being drilled 75 relatively large spaces 16 adjacent the flat faces 17 of the body 11 through which cuttings and drilling fluid may pass upwardly. Extending upwardly from the lower end of the body 11, an open slot 20 is cut or formed in a direction parallel to the side faces 17 of the body 11, thereby forming in the lower portion of the body 11 a pair of downwardly projecting flat legs or plates 21. Removably secured to the lower end of the body 11 is a cutter head 22 80 having an upwardly projecting wall or extension 23 of such lateral dimension that it will fit between the lower ends 24 of the legs or plates 21, there being horizontal grooves or channels 25 formed in the head 22 adjacent the sides of the 85 extension 23 in which the lower ends of the legs 21 rest when the cutter head is secured to the body 11, as shown in Figs. 1 and 2, to prevent spreading of the legs 21 under torsional strains should the nuts 26 of bolts 27 become 90 loosened from any cause. Two of the bolts 27 may be provided as shown, these bolts extending through openings 28 in the lower portions of the plates 21 and in the extension 23 of the 95 cutter head 22.

In this embodiment of the invention I have shown the cutter head 22 in cylindrical form with roller type rock cutters 30 and 31 secured thereto in position to penetrate downwardly and thereby produce a desired drilling operation. 105 The cutter head 22 is provided with passages 32 and 33 for the delivery of drilling fluid or mud to the cutters 30 and 31.

For the delivery of drilling fluid from the 110 lower end of the drilling string 14 to the upper

ends of the passages 32 and 33, I provide a tubular member 34 which extends downwardly in centralized position through the space or slot 20 between the legs 21. The extension 23 of 5 the cutter head 22 is provided with a counterbore 35 of a size to closely fit the lower end of the tubular member 34, the upper ends of the passages 32 and 33 communicating with the bottom of the counterbore 35 and consequently 10 with the lower end of the tubular member 34. The upper end of the member 34 passes through an axial opening 36 between the interior of the box 12 and the upper end of the slot or space 20, there preferably being a threaded engagement 15 of the upper end of the tubular member 34 with the wall of the opening 36, as shown at 37, so that the tubular member 34 can, by rotation, be threaded tightly downwardly into the counterbore 35. If desired, an annular gas- 20 ket 40 may be employed to seal the lower end 25 of the tubular member 34.

The portions of the slot or opening 20 lying on opposite sides of the tubular member 34, as shown in Fig. 3, provide reamer recesses 41 having lower end walls formed by the extension 23 of the cutter head 22. A further feature of the invention is that the securing of the cutter head 22 to the lower end of the bit body, as previously described, may operate to prevent loss 30 of the reamer elements from the reamer recesses 41, and to illustrate this feature of the invention I have in Fig. 2 shown roller type reamers 42 having shaft extensions or trunnions 43 and 44 extending respectively from the upper 35 and lower ends thereof. The extremities of these trunnions 43 and 44 extend into pockets 45 and 46 formed respectively in the upper wall of the slot or recess 20 and in the upper end face of the extension 23 by which the cutter head 40 is secured to the lower ends of the legs or plates 21. The trunnions or shaft extensions 43 and 44 are carried in roller bearings 47 consisting of roller members 48 preferably of cylindrical form, as shown in Fig. 2, operating in 45 races or cylindrical openings 50 formed in the ends of flat, laterally and horizontally extending plates 51 and 52 disposed at the upper and lower ends of the slot or opening 20. As shown in Fig. 3, the plates 51 and 52 are of rectangular 50 form with the ends thereof rounded as indicated at 53 and of such width that they closely fit between the inner faces 54 of the plates 21. Each of the plates 51 and 52 has an opening 55 therein of a diameter less than the width of 55 the plate, through which the tubular member 34 extends, the tubular member thus serving as a means for holding the plates 51 and 52 against lateral movement so that under ordinary use of the bit the engagement of the plates 51 and 60 52 by the tubular member 34 serves as a means for holding the reamer rollers 42 in operating positions in their respective reamer recesses 41. Should there be a breakage of the walls 57, Fig. 3, so that the end portions of the plates 51 and 65 52 would tend to slide outwardly in the reamer recesses 41, the engagement of the extremities of the trunnions 43 and 44 with the pockets 45 and 46 would then serve to prevent loss of the reamer rollers 42, and the bearings by which 70 they are supported, from the recesses 41.

The bearing means for supporting the reamer rollers 42 are of simple form. The races or cylindrical openings 50, in which the roller bearing members 48 operate, are closed at their lower 75 ends by integrally formed flanges 60, and are

closed at their upper ends by relatively thin plates 61 secured to the upper faces of the plates 51 and 52. In the use of the simple drilling tool disclosed, the removal of the bolts 27 makes possible the removal of the cutter head 22 and the reamer rollers 42 with their associated bearings 47 and the securing plates 51, 52, and 61, whereby the operations required to replace the worn parts of the bit are made very simple. 80

As shown in Fig. 4, the trunnions 43 and 44 may be shortened, and the recesses 45 and 46 may be omitted so that the engagement of the plates 51 and 52 by the tubular member 34 may serve as the sole means for holding the reamer devices in operative position in the reamer recesses 41. The construction shown in Fig. 2 is preferable, however, since two means for preventing loss of the reamer devices are provided: first, the engagement of the plates 51 and 52 by the tubular member 34, and second, the projection of the trunnions 43 and 44 into the pockets 45 and 46. In the form of the invention shown in Fig. 4, the reamers may be removed from the reamer recesses without the necessity of removing the cutter head 22 by unscrewing the tubular member 34 so that the openings 55 of the plates 51 and 52 will be disengaged, and the plates 51 and 52 with the reamer rollers 42 may be slid in lateral direction from the opening 20. A new assembly of parts 90 may then be inserted in the opening 20 and locked therein in operative position by replacing the tubular member 34 so that such tubular member will extend through the openings 55 in the plates 51 and 52 of the new assembly of 95 parts. 100

Relative to the feature of my invention concerning the holding of the reamer devices in the reamer recesses in consequence of the securing of the cutter head 22 to the lower end of the bit 115 body, I have in Figs. 5 and 6 shown a roller 42' supported in bearing blocks 65 and 66, the inner ends 67 of which engage the surface 68 of the tubular member 34 so that the inward movement of such blocks is thereby prevented. The blocks 120 65 and 66 have interlocking engagement with the upper and lower walls of the reamer recesses 41, such inter-engagement being shown in the engagement of pins 70 which project from the upper and lower walls of the bearing recesses 41 into companion openings 71 in the bearing blocks. The lower opening 71 projects upwardly from the upper face of the extension 23 of the cutter head 22. The removal of the cutter 125 head for the purpose of its replacement disengages the lower pin 70 from its cooperating opening 71 and also permits a downward movement of the reamer roller 42 and the upper bearing block 65 so that the upper bearing block may be disengaged from the upper pin 70. 130

Although I have herein shown and described my invention in simple and practical form, it is recognized that certain parts or elements thereof are representative of other parts, elements, or 140 mechanisms which may be used in substantially the same manner to accomplish substantially the same results; therefore, it is to be understood that the invention is not to be limited to the details disclosed herein but is to be accorded the 145 full scope of the following claims.

I claim as my invention:

1. A rotary bit of the character described, including: a body having means at its upper end for connecting it to a string of drill pipe, said 150

- body having a pair of flat legs extending downwardly in parallel relation so as to form a recess open at its sides and at its lower end; a cutter head having an extension projecting upwardly therefrom so as to fit between the lower ends of said legs, there being fluid discharge passages extending downwardly within said head from said extension; a tubular member extending substantially vertically from the upper part of said body and centrally through said recess into engagement with said extension, to deliver drilling fluid from the upper part of said body to the fluid passages of said head; means extending laterally through the lower ends of said legs and said extension for securing said head to said body; and reamer elements mounted in said recess above said extension and on opposite sides of said tubular member.
2. A rotary bit of the character described, including: a body having means at its upper end for connecting it to a string of drill pipe, said body having a pair of flat legs extending downwardly in parallel relation so as to form a recess open at its sides and at its lower end; a cutter head having an extension projecting upwardly therefrom so as to fit between the lower ends of said legs, there being fluid discharge passages extending downwardly within said head from said extension; a tubular member extending substantially vertically from the upper part of said body and centrally through said recess into engagement with said extension, to deliver drilling fluid from the upper part of said body to the fluid passages of said head; means extending laterally through the lower ends of said legs and said extension for securing said head to said body; reamer elements mounted in said recess above said extension and on opposite sides of said tubular member; and means associated with said head for providing an engagement with said reamer elements when said head is secured to said body to prevent removal of said reamer elements from said recess.
3. A rotary bit of the character described, including: a body having means at its upper end for connecting it to a string of drill pipe, said body having a pair of flat legs extending downwardly in parallel relation so as to form a recess open at its sides and at its lower end; a cutter head having an extension projecting upwardly therefrom so as to fit between the lower ends of said legs, there being fluid discharge passages extending downwardly within said head from said extension; a tubular member extending substantially vertically from the upper part of said body and centrally through said recess into engagement with said extension, to deliver drilling fluid from the upper part of said body to the fluid passages of said head; means extending laterally through the lower ends of said legs and said extension for securing said head to said body; reamer elements mounted in said recess above said extension and on opposite sides of said tubular member; and means associated with said head for providing an engagement with said reamer elements when said head is secured to said body to prevent removal of said reamer elements from said recess.
4. A rotary bit of the character described, including: a body having means at its upper end for connecting it to a string of drill pipe, said body having a pair of flat legs extending downwardly in parallel relation so as to form a recess open at its sides and at its lower end; a cutter head having an extension projecting upwardly therefrom so as to fit between the lower ends of said legs, there being fluid discharge passages extending downwardly within said head from said extension; a tubular member extending substantially vertically from the upper part of said body and centrally through said recess into engagement with said extension, to deliver drilling fluid from the upper part of said body to the fluid passages of said head; means extending laterally through the lower ends of said legs and said extension for securing said head to said body, there being pockets in the upper part of said head to receive the lower extremities of said legs; and reamer elements mounted in said recess above said extension and on opposite sides of said tubular member.
5. A drilling device of the character described, including: a body having means at its upper end for connecting it to a string of drill pipe, cutting means at its lower end, and a diametral opening through an intermediate portion thereof; a plate member extending through said opening, there being an opening through said plate member; a reamer member engaging an end of said plate member; and a tubular member extending vertically from an upper portion of said body to a lower part thereof, said tubular member extending across said opening of said body and said opening of said plate member to hold said plate member in said opening of said body.
6. A drilling device of the character described, including: a body having means at its upper end for connecting it to a string of drill pipe, cutting means at its lower end, and a diametral opening through an intermediate portion thereof; a lateral member extending through said opening, there being an opening through said lateral member; a reamer member engaging an end of said lateral member; and a tubular member extending vertically from an upper portion of said body to a lower part thereof, said tubular member extending across said opening of said body and said opening of said lateral member to hold said lateral member in said opening of said body.
7. A rotary bit of the character described, including: a body having means at its upper end for connecting it to a string of drill pipe, and having a pair of legs extending downwardly in parallel relation to form a recess open at the sides and lower end of said body; a head adapted to be secured to the lower ends of said legs, said head having an extension projecting upwardly between the lower extremities of said legs, there being means for securing said extension to the lower ends of said legs, said extension closing the lower end of said recess whereby to form an opening extending diametrically through said body; plates extending diametrically through said opening at the upper and lower ends thereof, the ends of said plates providing bearing means and the central portions of said plates having vertical openings therethrough; roller reamers disposed between adjacent ends of said plates and supported in adjacent bearings at the ends of said plates; and a member extending from the upper portion of said body substantially vertically through said diametral opening and through said openings in said plates into engagement with said head.

8. A rotary bit of the character described, including: a body having means at its upper end for connecting it to a string of drill pipe, and having a pair of legs extending downwardly in parallel relation to form a recess open at the sides and lower end of said body; a head adapted to be secured to the lower ends of said legs, said head having an extension projecting upwardly between the lower extremities of said legs, there being means for securing said extension to the lower ends of said legs, said extension closing the lower end of said recess whereby to form an opening extending diametrically through said body, and said head having fluid passages extending downwardly from said extension to deliver drilling fluid to the cutting zone of the bit; plates extending diametrically through said opening at the upper and lower ends thereof, the ends of said plates providing bearing means and the central portions of said plates having vertical openings therethrough; roller reamers disposed between adjacent ends of said plates and supported in adjacent bearings at the ends of said plates; and a tubular member extending from the upper part of said body substantially vertically through said diametrical opening and said vertical openings in said plates, into engagement with said head to deliver drilling fluid to said fluid passages of said head. 85
9. A rotary bit of the character described, including: a body having means at its upper end for connecting it to a string of drill pipe, and having a pair of legs extending downwardly in parallel relation to form a recess open at the sides and lower end of said body; a head adapted to be secured to the lower ends of said legs, said head having an extension projecting upwardly between the lower extremities of said legs, there being means for securing said extension to the lower ends of said legs, said extension closing the lower end of said recess whereby to form an opening extending diametrically through said body; plates extending diametrically through said opening at the upper and lower ends thereof, the ends of said plates having cylindrical openings therein to form races for bearing rollers, there being bearing rollers in said cylindrical openings, and the central portions of said plates having vertical openings therethrough; a reaming roller mounted in each end of said diametrical opening of said body, each reaming roller having trunnions projecting therefrom into bearing engagement with bearing rollers in adjacent ends of said plates, and through said plates into pockets formed respectively in said body and said extension of said head; and a member extending from the upper portion of said body downwardly through said diametrical opening and through said vertical openings in said plates into engagement with said head. 105
10. A rotary bit of the character described, including: a body having means at its upper end for connecting it to a string of drill pipe, and having a pair of legs extending downwardly in parallel relation to form a recess open at the sides and lower end of said body; a head adapted to be secured to the lower ends of said legs, said head having an extension projecting upwardly between the lower extremities of said legs, there being means for securing said extension to the lower ends of said legs, said extension closing the lower end of said recess whereby to form an opening extending diametrically through said body, and said head having fluid passages extending downwardly from said extension to de- 110
11. A rotary bit of the character described, including: a body having means at its upper end for connecting it to a string of drill pipe, and having a pair of legs extending downwardly in parallel relation to form a recess open at the sides and lower end of said body; a head adapted to be secured to the lower ends of said legs, said head having an extension projecting upwardly between the lower extremities of said legs, there being means for securing said extension to the lower ends of said legs, said extension closing the lower end of said recess whereby to form an opening extending diametrically through said body; plates extending diametrically through said opening at the upper and lower ends thereof, the ends of said plates having cylindrical openings therein to form races for bearing rollers, there being bearing rollers in said cylindrical openings, and the central portions of said plates having vertical openings therethrough; a reaming roller mounted in each end of said diametrical opening of said body, each reaming roller having trunnions projecting therefrom into bearing engagement with bearing rollers in adjacent ends of said plates, and through said plates into pockets formed respectively in said body and said extension of said head; and a member extending from the upper portion of said body downwardly through said diametrical opening and through said vertical openings in said plates into engagement with said head. 115
12. A rotary bit of the character described, including: a body having means at its upper end for connecting it to a string of drill pipe, said body having a pair of legs extending downwardly in parallel relation so as to form a recess open at its sides and at its lower end; a cutter head secured to the lower ends of said legs so that its upper wall will close the lower end of said recess, there being a fluid passage extending downwardly through said head; a tubular member extending substantially vertically from the upper part of said body and through said recess into engagement with said head, to deliver drilling fluid from the upper part of said body to the fluid passage of said head; and reamer elements mounted in said recess above said head and on opposite sides of said tubular member. 130
13. A rotary bit of the character described, including: a body having means at its upper end for connecting it to a string of drill pipe, said body having a pair of legs extending downwardly in parallel relation so as to form a recess open at its side and at its lower end; a cutter head 145
14. A rotary bit of the character described, including: a body having means at its upper end for connecting it to a string of drill pipe, said body having a pair of legs extending downwardly in parallel relation so as to form a recess open at its side and at its lower end; a cutter head 150

secured to the lower ends of said legs so that its upper wall will close the lower end of said recess, there being a fluid passage extending downwardly through said head; a tubular member extending substantially vertically from the upper part of said body and through the inner part of said recess into engagement with said head, to deliver drilling fluid from the upper part of said body to the fluid passage of said head; and a reamer element mounted in said recess.

14. A device of the character described, including: a body having means for securing it to a rotating means, there being an axial opening through said body and radial openings in

said body above the lower end thereof, the inner ends of said radial openings being in open communication with said axial opening; a tube extending through said axial opening for conducting drilling fluid past the inner ends of said radial openings; a toothed roller in each of said radial openings, each of said toothed rollers having shaft members projecting from the ends thereof; and bearing bodies slidably into the ends of said radial openings at the ends of said toothed rollers, said bearing bodies carrying roller type bearing means receiving said shaft members.
